R. L. LOUDERBACK,
HORSESHOE CALK,
APPLICATION FILED DEC. 21, 1914.

1,152,526.

Patented Sept. 7, 1915.

UNITED STATES PATENT OFFICE.

RAYMOND L. LOUDERBACK, OF MIDDLETOWN, OHIO.

HORSESHOE-CALK.

1,152,526.

Specification of Letters Patent. Patented Sept. 7, 1915.

Application filed December 21, 1914. Serial No. 878,398.

To all whom it may concern:

Be it known that I, RAYMOND L. LOUDERBACK, a citizen of the United States, residing at Middletown, in the county of Butler and State of Ohio, have invented certain new and useful Improvements in Horseshoe-Calks, of which the following is a specification.

This invention contemplates a new and improved horse shoe calk and has as its primary object to provide a device of this character adapted to be readily attached in wet weather or during the winter months when the roads are icy, to the shoe of a draft animal, although, it is to be understood, that the calk may be used under ordinary circumstances, in any instance where it is desired that the draft animal be roughly shod.

A further object of the invention is to provide a calk which will be adapted for attachment to the conventional type of horse shoe now in common use and which may be applied directly to the shoe upon the foot of a draft animal.

The invention has as a still further object to provide a horse shoe calk wherein the act of connecting the calk with the shoe of the animal will cause the calk to seat firmly against the shoe to thus provide a thoroughly rigid structure. And a still further object of the invention is to provide a horse shoe calk wherein the working element employed may be removed from the calk for the purpose of sharpening, or in the event it is desired, after an old working element has become worn out, to substitute a new one.

Other and incidental objects will appear as the description proceeds and in the drawings wherein I have illustrated the preferred embodiment of my invention and wherein similar reference characters designate corresponding parts throughout the several views, Figure 1 is a side elevation showing both the preferred and modified forms of my invention applied, the shoe being partly broken away and shown in section, however, to illustrate the modified form of the invention, Fig. 2 is a horizontal section showing the calk applied, Fig. 3 is a similar view illustrating the calk adjusted to engage the shoe, Fig. 4 is a bottom plan view of the calk, and Fig. 5 is a perspective view showing the parts of the calk detached from each other and arranged in proper relative position.

Coming now to more particularly describe the invention, it will be seen upon reference to the drawings that my improved horse shoe calk includes a body portion 10 which is preferably formed with a flat inner face as illustrated and which at one extremity is provided with a laterally extending flange 11. Formed integrally on the opposite extremity of the body portion are the spaced arms 12, the said arms projecting laterally from the body portion in the same direction with the flange 11 and being connected with the body portion adjacent the side edges thereof. Preferably, the body portion 10 is tapered longitudinally toward the flange 11 from a point immediately above the inner extremities of the arms 12, although, such configuration is, of course, purely arbitrary. The arms 12 extend in substantially parallel relation to each other and are cut away upon one side at the inner extremities thereof to provide inclined faces 13 sloping longitudinally of the arms laterally away from the body portion 10, the adjacent upper edges 14 of the arms, at the outer extremities thereof being preferably flat and smooth.

Disposed for detachable connection with the body portion 10 is a calk indicated as a whole at 15 in Fig. 5 of the drawings. It will be seen that the body portion 16 of the calk is substantially rectangular and is disposed to be received between the arms 12, the end walls of the body portion being flat to confront the flat inner faces of the arms 12, while the outer extremity thereof is preferably rounded as shown.

Medially formed in the body portion 16, is a longitudinally extending opening, which, adjacent the flat upper face 17 of the calk is enlarged and provided with inwardly converging walls to form a seat 18. Detachably engaging in said opening and secured therein in any suitable manner is a working element 19 which, at one extremity, is provided with a head 20 fitting within the seat 18 and provided with beveled side walls engaging the converging walls of the said seat, it being observed that when the working element 19 is operatively connected with the calk, the flat upper face of the head 20 is disposed flush with the flat upper face 17 of the body portion 16. At its extremity opposite the head 20, the working element 19 is cut away to provide a working edge 21.

It will be observed that the working element 19 is of such length as to extend well

beyond the lower extremity of the body portion 16 of the calk to engage the ground or roadway, and attention is called to the fact that in thus providing a detachable working element, the said element may be readily removed from the body portion of the calk for the purpose of sharpening if desired, or when it becomes worn away in use, a new working element may be readily substituted therefor.

Extending from opposite sides of the body 16 of the calk adjacent the upper extremity thereof are laterally projecting lugs or flanges 22 disposed to bear over the arms 12, for operatively connecting the calk with the body portion 10, and the said lugs upon one side thereof are cut away to provide the transversely beveled shoulders 23 disposed to seat upon the shoulders 13 of the said arms.

Formed integrally with the body portion 16 and extending laterally from the upper extremity thereof, is an externally screw threaded shank 24 which is arranged medially of the body portion and is disposed to extend longitudinally between the arms 12, it being observed upon reference to Figs. 2 and 4 of the drawings, that the said shank is disposed in a plane with the arms. Detachably fitting upon the shank 24 is an internally screw threaded locking nut 25.

Coacting with the body portion 10 is a clamping plate 26 which is provided with an opening 27 medially thereof, substantially, disposed to loosely receive the shank 24. Upon its side edges, and adjacent one extremity thereof, the plate 26 is formed with oppositely disposed notches 28, adapted to receive the arms 12, the plate being slidable longitudinally upon the arms. At opposite extremities, the plate 26 is provided with laterally extending confronting flanges 29 and 30, the flange 29 being disposed to bear beneath the shank 24, while the flange 30 is arranged to confront the flange 11 to coact therewith.

Having thus described the construction of the calk, the manner in which it is applied will now be explained.

The body portion 10 of the calk is arranged upon the heel of the shoe in the rear of the hoof of the animal as illustrated in Fig. 1 of the drawings with the flat inner face thereof seating against the outer edge of the shoe and with the flange 11 engaging over the upper face thereof, it being observed that the flat upper edges of the arms 12 are thus disposed to rest or seat against the lower face of the shoe. The calk proper is then applied with the body portion 16 thereof disposed between the arms 12 and with the shoulders 23 seating upon the shoulders 13 in which position, it will be observed that the upper flat face of the body portion 16 confronts the lower face of the

shoe, while the shank 24 extends out beneath the hoof of the animal. The clamping plate 26 is then applied in the manner heretofore set forth to bear against the inner edge of the shoe with the flange 13 engaging over the upper face thereof. The locking nut 25 is then adjusted upon the shank 24.

It will be noted upon reference to Fig. 2 of the drawings that when initially applied, the heel of the shoe will be held loosely between the flanges 11 and 30 and the upper face of the body portion 16 of the calk proper, and particular attention is now directed to the manner in which the said calk is brought into binding engagement with the shoe.

The nut 25 is moved inwardly upon the shank 24 to engage the clamping plate 26 which, in turn, will correspondingly move the body portion 16 of the calk longitudinally between the arms 12. It will be seen that as the body portion 16 is thus moved, the shoulders 23 will ride upwardly upon the shoulders 13 toward the flanges 11 and 30 to securely bind the body of the shoe between the calk 15 and the said flanges. Thus, the entire structure may be rigidly secured to the shoe and it will be observed that the action of operatively connecting the calk with the shoe will also cause the calk to rigidly seat thereagainst. Furthermore, attention is called to the fact that the lower face of the shoe will bear over the head 20 of the working element 19 to thus assist in securely maintaining said working element in position within the body portion 16 of the calk.

From the foregoing description, it will, of course, be readily understood that the calk may be readily applied to the shoe of a draft animal or removed as desired, and for this purpose any suitable type of wrench may be employed.

It is intended, in use, that one of my improved calks shall be connected with the heel of the shoe of the draft animal upon each side thereof so that an even tread will be presented.

In Fig. 1 of the drawings, I have illustrated a slight modification of the invention in the form of a calk particularly adapted to be applied to the toe portion of a shoe. In this form of the invention, the clamping plate 26 is made relatively shorter than as embodied in the preferred form, and the flange 30 is disposed to engage within a suitable notch or slot 33 formed in the inner edge of the shoe. This construction is necessary owing to the presence of the hoof of the animal bearing over the upper face of the shoe, making it impracticable to connect the clamping plate 26 with the shoe at the toe portion thereof, as in the preferred form of the invention. Otherwise, the construction disclosed in this modification is

identical with that found in the preferred embodiment of the invention and a further description thereof, will not, therefore, be given.

5 Having thus described my invention, what I claim and desire to secure by Letters Patent is:—

1. A device of the character described including a body portion adapted to engage a 10 horse shoe and provided with an inclined shoulder sloping toward the shoe, a calk carried by the body portion and provided with an inclined shoulder seating upon said first mentioned shoulder, a clamping plate 15 coacting with the body portion and adapted to engage the shoe, and means operatively engaging the calk and coacting with the clamping plate for moving the said plate toward the body portion and for moving the 20 shoulder of the calk upon the shoulder of the body portion to bring the calk into binding engagement with the shoe.

2. A device of the character described including a body portion adapted to engage a 25 horse shoe and provided with a shoulder sloping toward the lower face of the shoe, a calk operatively supported by the body portion to confront the lower face of the shoe and provided with a shoulder seating upon 30 said first mentioned shoulder, a clamping plate coacting with the body portion and adapted to engage the shoe, and means operatively engaging the calk and coacting with said clamping plate for moving the said 35 plate toward the body portion and for moving the shoulder of the calk upon the shoulder of the body portion to bring the calk into binding engagement with the lower face of the shoe.

40 3. A device of the character described including a body portion adapted to engage over the upper face of a horse shoe and provided with arms extending beneath the lower face of the shoe, the said arms having 45 inclined shoulders formed thereon, a calk supported by said arms and provided with inclined shoulders seating upon said first mentioned shoulders, a clamping plate coacting with the body portion and adapted 50 to engage over the shoe, and means coacting with the said clamping plate and operatively engaging the calk whereby the calk is brought into binding engagement with the lower face of the shoe.

55 4. A device of the character described including a body portion adapted to engage a horse shoe, said body portion having arms formed thereon provided with inclined shoulders, a calk supported by said arms 60 and movable longitudinally thereof, the said calk being provided with inclined shoulders seating upon said first mentioned inclined shoulders, a clamping plate coacting with the body portion and adapted to engage the 65 shoe, and means operatively engaging the

calk and coacting with the said clamping plate for moving the calk longitudinally between said arms.

5. A device of the character described including a body portion adapted to engage a 70 horse shoe, said body portion having spaced arms formed thereon provided with inclined shoulders, a calk supported by said arms and movable longitudinally thereof, said calk being provided with inclined shoulders seating upon said first mentioned shoulders and having a shank extending therefrom, a clamping plate formed to receive the shank and said arms, the said clamping plate being movable longitudinally upon the arms and 75 being adapted to coact with the body portion to engage the shoe, and means adjustable longitudinally upon the shank and coacting with the clamping plate for moving the calk longitudinally between said arms. 80

6. A device of the character described including a body portion adapted to engage over the upper face of a horse shoe, said body portion being provided with spaced arms disposed to extend beneath the lower 90 face of the shoe, the said arms having inclined shoulders formed thereon sloping toward the said lower face of the shoe, a calk supported by said arms and movable longitudinally thereof, said calk being provided with inclined shoulders seating upon said first mentioned shoulders and having a shank extending therefrom, a clamping plate formed to receive said shank and said 95 arms, said clamping plate being movable longitudinally upon the arms and being adapted to coact with the body portion to engage the shoe, and means adjustable upon the shank and coacting with said clamping plate for moving the calk longitudinally between said arms into binding engagement with the lower face of the shoe. 100

7. A device of the character described including a body portion having a flange formed thereon adapted to engage over the upper face of a horse shoe and being provided with spaced arms disposed to extend beneath the lower face of the shoe, the said arms adjacent the body portion having inclined shoulders formed thereon, a calk supported by said arms and movable longitudinally thereof, said calk being provided with inclined shoulders seating upon said first mentioned shoulders and having a shank extending therefrom, a clamping plate 110 formed to receive said shank and having notches formed therein to receive said arms, said plate being provided with a flange adapted to engage the shoe and being disposed to coact with the body portion, and means adjustable upon the shank and coacting with the clamping plate for moving the calk longitudinally between said arms into binding engagement with the lower face of the shoe. 115

8. A device of the character described including a body portion having a flange formed thereon adapted to engage over the upper face of a horse shoe and being provided with spaced arms disposed to extend beneath the lower face of the shoe, the said arms adjacent the body portion having inclined shoulders formed thereon, a calk supported by said arms and movable longitudinally thereof, said calk being provided with inclined shoulders seating upon said first mentioned shoulders and having a shank extending therefrom, a clamping plate 120 formed to receive said shank and having notches formed therein to receive said arms, said plate being provided with a flange adapted to engage the shoe and being disposed to coact with the body portion, and means adjustable upon the shank and coacting with the clamping plate for moving the calk longitudinally between said arms into binding engagement with the lower face of the shoe. 125

8. A device of the character described including a body portion adapted for attachment to a horse shoe, a calk operatively supported by the body portion and independently adjustable thereon in vertical and horizontal planes, a clamping plate coacting with the body portion and adapted to engage the shoe, and means coacting with the clamping plate and operatively engaging the calk for adjusting the said calk.
9. A device of the character described including a body portion adapted to engage a horse shoe, a calk operatively supported by the body portion and simultaneously adjustable independently thereon in vertical and horizontal planes, a clamping plate coacting with the body portion and adapted to engage the shoe, and means coacting with the clamping plate and operatively engaging the calk for adjusting the calk.
10. A device of the character described including a body portion adapted for attachment to a horse shoe, a calk adjustable upon the body portion independently thereof to engage the shoe, said calk including a

working element detachably connected thereto, a clamping plate coacting with the body portion and adapted to engage the shoe, and means coacting with the clamping plate and operatively engaging the calk for adjusting the said calk.

11. A device of the character described including a body portion adapted for attachment to a shoe and having a shoulder formed thereon, a calk operatively supported by the body portion and independently adjustable thereon to engage the shoe, said calk being provided with a shoulder coacting with said first mentioned shoulder, a clamping plate coacting with the body portion and adapted to engage the shoe, and means coacting with the clamping plate and operatively engaging the calk for adjusting the said calk.

In testimony whereof I affix my signature in presence of two witnesses.
